UNITED STATES PATENT OFFICE.

WILLARD M. FARROW, OF WASHINGTON, DISTRICT OF COLUMBIA.

DENTAL IMPLEMENT.

1,233,770.

Specification of Letters Patent. Patented July 17, 1917.

Application filed May 25, 1917. Serial No. 170,922.

To all whom it may concern:

Be it known that I, WILLARD M. FARROW, a citizen of the United States, residing at Washington, in the District of Columbia, 5 have invented certain new and useful Improvements in Dental Implements, of which the following is a specification.

This invention relates to certain new and useful improvements in dental appliances 10 and more particularly to dental tongs of that character designed for handling amalgam and analogous substances and it has for its objects among others to provide a simple and cheap, yet efficient and reliable device 15 of this character embodying in the one implement tweezers for grasping the amalgam or other substance and a plunger, the latter being reciprocable within or between the arms of the tweezers and having means 20 whereby the plunger may be held distended by pressure on the tweezers to force the amalgam or other substance into the cavity of the tooth. It has for a further object to provide a device of this character embody- 25 ing few parts, those simple in their nature, readily assembled, easily manipulated and not liable to get out of order.

Other objects and advantages of the invention will hereinafter appear and the 30 novel features thereof will be particularly pointed out in the appended claims.

The invention is clearly illustrated in the accompanying drawings, which, with the 35 numerals of reference marked thereon, form a part of this specification, and in which—

Figure 1 is an elevation of my improved dental implement.

Fig. 2 is a similar view showing the plunger distended and held against longitudinal 40 movement.

Fig. 3 is a view at right angles to Fig. 1.

Fig. 4 is a substantially central longitudinal section through the device with portions broken away.

Fig. 5 is a transverse section on the line 5-5 of Fig. 2, looking in the direction of the arrows.

Fig. 6 is a transverse section on the line 6-6 of Fig. 2, looking in the direction of the arrows.

Fig. 7 is an enlarged detail in elevation of the end of the plunger with a portion broken away.

Fig. 8 is a detail of the plunger removed. 55 Like numerals of reference indicate like parts throughout the several views.

Referring to the drawings,

1 designates the handle or body portion of suitable material, shape and size. It is provided with a longitudinal bore 2 in which is 60 adapted to reciprocate the stem 3 of the reciprocating member 4, the outer end of which is provided with a head or the like 5 which may be milled or otherwise roughened for an evident purpose. The other end of the body 65 or member 1 has a bore and opening 6 through which reciprocates the member 4, any suitable means, as for instance, a pin 7 passed through the member 4 and adapted to engage the end of the body 1, being 70 provided to limit the movement of the member 4 outward. This member 4 is normally held in the outward or distended position in which it is seen in Figs. 1, 3 and 4, by means of a spring 8 coiled around the member 4 75 within the casing 1 bearing at one end against the shoulder 9 of the member 4 and at the other end against the end wall of the bore 2 of the body 1. When the member 4 is forced in the direction of the arrow seen 80 in Fig. 4, the spring is compressed. When pressure is removed from the head or thumb-piece 5, the spring forces the parts into their normal position, that seen in Fig. 4.

The end of the body or casng 1 adjacent 85 the end is cut away or halved out, as at 10, to receive the adjacent ends of the tweezers 11 which are secured thereto by rivets or the like 12, as seen in Fig. 3.

The outer ends of the two portions of the 90 tweezers are made substantially semi-circular in cross section, as seen at 13 in Fig. 5, their outer faces being rounded and tapered, as seen at 14 in Fig. 3.

The free end of the member 4 is formed 95 into a plunger 15, as seen best in the enlarged view Fig. 7, the extreme end being reduced and rounded, as seen at 16, forming the shoulder 18, as seen clearly in Fig. 7, and adjacent the shoulder 18 is a tapered portion 100 20, also shown clearly in Fig. 7.

In practice these parts are normally as seen in Fig. 1. The operator, taking the device in his hand, engages the amalgam or gold or other substance with the points of 105 the tweezers, placing his thumb and finger on the latter and holding the head 5 against the palm of the hand. When the amalgam has been picked up, it is carried to the cavity and when in place all that it is necessary for 110 the operator to do is to apply pressure by the thumb or finger, or the palm of the

hand against the head 5, when the member 4 will be pressed in the direction of the arrow in Fig. 4, compressing the spring and forcing the plunger 15 outward beyond the ends 5 of the tweezers. Then, by pressure upon the tweezers adjacent their free ends, they are forced inward into engagement with the shoulder 18 of the plunger, as seen in Figs. 7 and 8, when the implement can be used as 10 a plunger to force the amalgam or gold into the cavity of the tooth. It will thus be seen that the one device is capable of use both as tweezers for conveying the amalgam or gold to the cavity in the tooth, and then for 15 forcing the amalgam or gold into such cavity, without the necessity of having to put the one implement down and picking up another, thus avoiding the liability of losing the amalgam as is likely to occur under ordinary conditions. The conical portion 20 allows the ends of the tweezers to be firmly compressed and still hold their ends against the shoulder.

Modifications in details, within the scope 25 of the appended claims, may be resorted to without departing from the spirit of the invention or sacrificing any of its advantages.

What is claimed as new is:—

1. A dental implement comprising tweezers with an extended body portion and having substantially semi-circular free ends and a spring-actuated plunger movable between the tweezers and engageable by the ends of the tweezers to hold the same against longitudinal movement.

2. A dental implement comprising tweez-

ers having substantially semi-circular free ends and a plunger movable between the tweezers and having a shoulder for engagement by the ends of the tweezers to hold the 40 plunger and tweezers in fixed operative relation.

3. A dental implement comprising a bored casing, tweezers carried thereby and having substantially semi-circular free ends, and a 45 spring-actuated member movable in said casing and having at its outer end a plunger with shoulder for engagement by the ends of the tweezers.

4. A dental implement comprising a body 50 portion and tweezers carried thereby, and a spring-actuated member movable through said body portion and carrying at one end a plunger with a shoulder for engagement with the ends of the tweezers and a tapered 55 portion against which the ends of the tweezers may be compressed.

5. A dental implement comprising a body portion and tweezers carried thereby and having substantially semi-circular free ends, 60 a spring-actuated member movable through said body portion and carrying at one end a plunger having a rounded end and formed with a shoulder for engagement with the ends of the tweezers, and a tapered portion 65 adjacent said annular portion.

In testimony whereof I affix my signature in the presence of two witnesses.

WILLARD M. FARROW.
